FEED MECHANISM FOR SEWING MACHINES
AND THE LIKEGeorge Sauer, Berwyn, Ill., assignor to Union
Special Machine Company, Chicago, Ill., a cor-
poration of Illinois

Application April 21, 1937, Serial No. 138,087

5 Claims. (Cl. 112—207)

My invention relates to feed mechanism for sewing machines and the like. The types of underfeeds commonly used on ordinary sewing machines (e. g., a four-motion feed-dog beneath the fabric, coacting with a spring-pressed presser-foot above) answer very well in many cases; but for certain kinds of sewing, a more positive feeding of the upper fabric layer is desirable,—as when the fabric layers being sewed together tend to slip over one another—and especially if the fabric is very thick or heavy. Feed mechanism for such purposes is shown and described in my pending application Serial No. 55,502, filed December 21, 1935, in which a needle vibrating laterally in the line of feed coacts with any suitable underfeed.

My present invention relates to feed mechanism by which fabric layers can be fed even more positively, and by which various other advantages can be obtained. For the purposes of my invention, I provide novel feed mechanism of laterally vibrating type above the work, preferably associated with a laterally vibrating needle or needles, and with suitable feed means beneath the work, such as a four-motion feed-dog. With the upper vibrating feed device and the needle moving together in the same direction as the underfeed, a very powerful feeding action for heavy or slippery fabrics is obtained. Other features and advantages of the invention will appear from the following description of a species or form of embodiment, and from the drawing.

In the drawings, Fig. I is a side view of a lock-stitch type of sewing machine embodying my invention, the main frame of the machine being in vertical mid-section.

Fig. II is a view from the left of Fig. I, omitting the parts below the work-support, and with parts of the needle head broken out.

Fig. III is a side view showing the needle head in vertical longitudinal mid-section, from the left of Fig. II.

Fig. IV is a view from the left of Fig. I, with most of the parts above the work-support broken away and omitted.

Fig. V is a fragmentary plan and horizontal sectional view of the needle head and parts therein.

Fig. VI is a view similar to Fig. II showing different positions of certain parts, with portions of the needle head and other parts partially broken away.

Fig. VII is a view similar to Figs. II and VI showing other positions of certain parts, also with some parts partially broken away.

Fig. VIII is a fragmentary plan view of the

operating connection between an oscillatory needle-bar and feed-bar guide and its actuating crank.

Fig. IX is a perspective view of a link forming part of the top-feed mechanism. 5

Fig. X is a bottom plan view of the work support and the associated parts and mechanisms.

Fig. XI shows a section taken as indicated by the line and arrows XI—XI in Fig. X, with certain parts partly broken away. 10

As shown in Figs. I, II, and III, the hollow frame of the sewing machine here illustrated carries a work support 10 and includes a hollow arm 11 projecting from an upright standard 12 and carrying a needle head 13. With the head 13 are associated a vertically reciprocating needle bar 15 carrying the needle 16, and a spring actuated presser bar 17 carrying a presser foot 18. The presser bar 17 is mounted in the head 13 so as to be vertically movable, and is yieldingly urged 20 downward by a helical compression spring 19, as usual. Beneath the work support 10 are shown in Figs. I and IV a four-motion feed dog 20, having a suitably serrated or roughened feeding surface that coacts with the presser foot 18 through 25 an opening in the work support 10, and stitch forming mechanism 21 for coacting with the needle 16. As shown, the stitch forming mechanism 21 includes a rotary hook or loop taker 22 revolving in a horizontal plane beneath the work 30 support 10, about a vertical axis. This stitch-forming mechanism 21 may be of any suitable construction, but is here shown as like that illustrated and described in the application of Norman V. Christensen and Oscar Quist, Serial No. 53,552, 35 filed December 9, 1935, and assigned to the assignee of this application.

It will be understood that the machine may be provided with any usual accessories (not shown), such as a thread tension, take-up, presser foot 40 lifting means, tension relieving device, and thread guides, and that these may be of any suitable or preferred construction, and may be operated by any suitable means. These and other accessories are more fully illustrated and described in the aforementioned application of Norman V. Christensen and Oscar Quist. 45

As shown in Figs. I, II, III, V, VI, and VII, the needle bar 15 reciprocates in a guide bracket 30 which is pivoted on a stud 31 secured in the lower 50 end of the head 13, and includes upper and lower guide bearings 32 and 33 for said needle bar. Openings in the upper and lower ends of the head 13 afford clearance for the needle bar 15 to swing or oscillate relative to the head. The needle bar 55

- 15 may be actuated for its up and down movement from a horizontal drive shaft 35 (mounted in bearings 36, 36 in the arm 11) by any suitable means, such as a crank 37 on the end of the shaft 35 with a pitman connection 38 from its crank pin 39 to a pivot pin 40 suitably mounted on the needle bar. As shown, see also Fig. VIII, the guide bracket 30 is oscillated about its pivot 31 from a horizontal shaft 41 mounted above the shaft 35 10 in bearings 42, 42 in the arm 11, by means comprising a rocker arm or crank 44 fixed to the end of the shaft 41 and provided with a pivot pin 45 whose flattened end 46 is slidably engaged in a vertical slot or groove in the upper portion 32 of the bracket 30. The shaft 41 may preferably be driven from the shaft 35 by means adapted to impart an adjustably variable oscillation to said shaft 41. The mechanism shown in Fig. I for actuating shaft 41 from shaft 35 includes an eccentric 47 on said shaft 35 with an eccentric rod connection 48 to a crank 49 fast on the adjacent end of shaft 41. The eccentric 47 is directly adjacent a corresponding bearing 36 at the driven ends of the shafts 41 and 35, which actuate guide 25 30, needle bar 15, and other parts from their remote or distal ends in the head 13. For adjusting the amplitude of oscillation imparted to shaft 41, and through it to the needle bar guide 30, provision may be made for adjusting eccentric 47 30 radially or diametrically of shaft 35, by any suitable means, not shown, such as that set forth in my application Serial No. 55,502, filed December 21, 1935.

35 The mechanism thus far described is substantially like that set forth in my above-mentioned application Serial No. 55,502.

For the purposes of my present invention, there is shown an upper feeding foot 50 on the lower end of a bar 51 that partakes of the oscillatory work feeding movements of the needle 18, and acts conjointly with the lower four-motion feed dog 20, or other suitable lower feed. As shown in Figs. II and III, the bar 51 is mounted or journaled for up and down movement in a bore 45 in the guide bracket 30 for the needle bar 15. The feeding foot 50 is engaged with the work while moving in the direction of feed, and is raised out of contact with the work for its return movement. Correlatively, the presser foot 50 50 18 should be raised while the foot 50 is feeding the work, and lowered to clamp the work when the foot 50 is raised.

As shown in Figs. II and III, the feeding foot 50 moves to and fro in a longitudinal slot in the presser foot 18, directly opposite the feed dog 20, so that the work is as it were almost "clamped" between the parts 20 and 50 during their feeding movement. A rocking (bell-crank) lever 52 is pivotally connected or fulcrumed by a pin 53 to a bracket 54 which is adjustably fixed on the presser bar 17, by set-screws 55, and is also pivotally connected or fulcrumed by pins 56 and a (vertical) link 57 to the upper end of feeding foot bar 51. This link 57 is clearly shown in Fig. IX. In the present instance, the angle of the rocker 52 is pivoted at 53 to the presser bar bracket 54, and the end of its (horizontal) arm 58 is pivoted to feed foot bar 51 through link 57. The other (downward extending) arm 59 of the rocker 52 is suitably actuated to oscillate the rocker, and thereby depress and lift presser foot 18 and feed foot 50 in alternation,—as by an eccentric-crank 60 on the (lower) revolving shaft 35, with an eccentric strap and rod connection 61 pivoted by a pin 62 to the

lower end of this rocker arm. In general, the lower rotating shaft 35 is preferable to the upper oscillating shaft 41 as a source of motion for actuating the rocker 52. As here shown, the bracket 54 is also used for raising the presser foot 18 and the feed foot 58 from the work when desired, by means of a cam-lever 63 engaging under a laterally projecting arm 64 on the bracket. 5

As the rocker 52 lifts the presser foot 18, as shown in Fig. II, it pivots or fulcrums on the bar 51 while this bar is sustained by feeding foot 50, and vice-versa. When the presser foot 18 is lifted off the work by rocker 52 against spring 19, the pressure of the spring is of course applied through rocker 52 to hold feed foot 50 pressed against the work. Following the cycle of operation, it will be seen that as the shaft 35 revolves clockwise one-quarter revolution, the crank 37 will raise needle 18 from its lowest position as shown in Fig. II to its mid-position as shown in Fig. VI, where it has just risen above the work. During this movement, the presser foot 18 is at first up, the feed foot 50 is down, so that the rocker 52 fulcrums on link 57, and the feed foot 50 and the needle 18 are being swung by the action of crank arm 44 on rock-shaft 41 (and are feeding the work) to the right, to their mid-position shown in Fig. VI. By the end of this quarter-revolution of shaft 35, the rocker arm 59 has been moved by eccentric 60 from its extreme left-hand position shown in Fig. II to its mid-position as shown in Fig. VI, and the presser foot 18 has been lowered to rest on the work, as well as the feed foot 50. In the second quarter-revolution of shaft 35, the crank 37 raises the needle 18 from its mid-position shown in Fig. VI to its highest position as shown in Fig. VII, and the eccentric 60 swings rocker arm 59 to its extreme right-hand position as shown in Fig. VII, the rocker 52 fulcruming on bracket 54 and raising feed foot 50 off the work as shown. During this quarter-revolution of shaft 35, the needle 18 and the feed foot 50 are swung back to the left by the action of crank arm 44 on shaft 41, to the same positions as in Fig. II, as shown in Fig. VII. In the third quarter-revolution of shaft 35, the needle 18 and the feed foot 50 are swung further to the left by shaft 41, the feed foot 50 is lowered upon the work, and the needle 18 is lowered to its mid-position just above the work. In the fourth quarter-revolution of shaft 35, the crank 37 depresses needle 18 (through the work) to its lowest position shown in Fig. II, the fulcrum of rocker 52 shifts from bracket 54 back to link 57 and feed foot 50, so that the rocker 52 raises the presser foot 18 off the work as shown in Fig. II, and shaft 41 swings needle 18 and feed foot 50 to the right back to their positions shown in Fig. II. Thus the cycle is completed.

To obtain the sequence of operations above described, the eccentric 60 is set about 90° ahead of crank 37, and the eccentric 47 that operates shaft 41 from shaft 35 is likewise set about 90° ahead of crank 37. The amplitude of the work-feeding movement of needle 16 and feed foot 50 can be adjusted by adjusting the throw of eccentric 47 as already mentioned; and that of feed-dog 20 can likewise be adjusted as herein-after explained. By these adjustments, the upper feed by needle 16 and foot 50 may be made to correspond accurately with the lower feed by dog 20, or may be made greater or less in any desired proportion.

The feed-dog 20 and its actuation as now to be described are the same as set forth in my aforesaid application Serial No. 55,502.

As shown in Fig. I, a horizontal shaft 65 mounted in bearings 66, 66, 80 beneath the work support 10 is driven from the shaft 35, as by means of helical gears 67, 67 of equal diameters on the shafts 35 and 65, and an interposed coacting idle gear 68 on a short intermediate shaft 69. From the lower horizontal shaft 65, the stitch mechanism 21 and the feed-dog 20 may be driven by any suitable means. As best shown in Fig. IV, the feed-dog 20 is mounted for up and down adjustment (as by a bolt and slot connection 71) on a four-motion feed-bar 72. The feed member comprising feed-dog 20 and feed-bar 72 receives up and down motion from the horizontal shaft 65 by means of an eccentric 75 fast on shaft 65 and acting through an eccentric strap and rod 76 pivoted at 77 to a forward-extending curved arm 78 of feed-bar 72.

Bracket 80 and rotary hook stitch mechanism 21 are shown as like corresponding parts in the aforementioned Christensen and Quist application, and as similarly engaged with and adjustable along a tongued depending flange 81 on the work-support 10, to which flange they are secured by bolt and slot connections 82, 82. The stitch mechanism 21 is shown as revolving in a horizontal plane beneath the work support 10 about a vertical axis, and as driven from shaft 65 through bevel gears 83, 83, best shown in Fig. X.

The feed member comprising dog 20 and feed-bar 72 may receive horizontal, to and fro, work-feeding motion from an eccentric 85 on shaft 65, Figs. X and XI. As shown in Fig. IV, a forward-extending arm 86 of feed-bar 72 is pivotally connected at 87 to the upper end of a bifurcated arm 88 fast to one end of a horizontal shaft 90 that is journaled in bearing lugs 91 depending from the work-support 10. As here shown, shaft 90 is under the front edge of work support 10. Shaft 90 may be rocked or oscillated from eccentric 85 through actuating connections including an eccentric strap and rod 92 pivoted at 93 to the joint of a toggle device 94, 95. The lazy-bar link 94 of this toggle device is pivoted at 96 to a bracket 97 depending from the work-support 10, while the more active toggle link 95 is pivotally connected to a rocker arm 98 fast to shaft 90. The amplitude of movement thus imparted to shaft 90 and feed-dog 20 may be adjusted and varied by any suitable means, as by a slot and screw-clamp connection between rocker 98 and the pivot 99 which connects link 95 to said rocker. By this adjustment and the adjustment of eccentric 47 as already mentioned in connection with Figs. I-III, the feeding action of dog 20 can be made to correspond accurately with that due to the vibratory or oscillatory movement of needle 16, or may be made greater or less in any desired proportion. As shown in Fig. X, set collars 100, 100 secured on shaft 90 control its longitudinal position in its bearings 91.

Having thus described my invention, I claim:

1. In a sewing machine, the combination with a frame carrying a work support and including an arm overhanging said work support, a presser-foot bar mounted on said arm, a reciprocating needle bar, and an upper feeding foot bar, a guide for the movement of said feeding foot bar rockably fulcrumed on said arm, a drive shaft mount-

ed in bearings on said arm with actuating connections for reciprocating said needle bar, and a rocking lever fulcrumed on said arm with pivotal connections above said drive shaft to said presser foot and feeding foot bars, of means for actuating said lever from said drive shaft connected to the lever below its said pivotal connections, and means for oscillating said guide and said feeding foot bar operatively connected to the guide at a point further from the aforesaid guide fulcrum than said guide fulcrum is from the work, so that the to and fro motion of said guide at its connection to said oscillating means exceeds the resulting feed of the work by the feeding foot.

2. In a sewing machine, the combination with a frame carrying a work support and including an arm overhanging said work support, a presser-foot bar mounted on said arm, a reciprocating needle bar, and an upper feeding foot bar, and a guide for the movement of said feeding foot bar rockably fulcrumed on said arm, of upper and lower shafts above the guide fulcrum mounted in bearings on said arm, with actuating connections from one of said shafts to said guide, above said fulcrum, for rocking the guide, and from the other of said shafts to said needle bar for reciprocating it, a rocking lever fulcrumed on said arm with pivotal connections to said presser foot and feeding foot bars, and with an arm extending downward, and eccentric crank means on one of said shafts operatively connected to said downward-extending lever arm, to rock said lever.

3. In a needle-feed sewing machine, the combination of a presser-foot bar, a reciprocating needle bar and an upper feeding foot bar, a rockably fulcrumed guide for the movement of said needle and feeding foot bars, a drive shaft with actuating connections for reciprocating said needle bar, a rocking lever with pivotal connections above said drive shaft to said presser foot and feeding foot bars, means for actuating said lever from said drive shaft connected to the lever below its said pivotal connections, and means for oscillating said guide and said needle and feeding foot bars operatively connected to the guide at a point further from the work than the guide fulcrum, so that the guide and said needle and feeding foot bars function as a lever of the first class with respect to the work.

4. In a needle-feed sewing machine, the combination of a presser-foot bar, a reciprocating needle bar and an upper feeding foot bar, a rockably fulcrumed guide for the movement of said needle and feeding foot bars, upper and lower shafts above the guide fulcrum, with actuating connections from one of said shafts to said guide, above said fulcrum, for rocking the guide, and from the other of said shafts to said needle bar for reciprocating it, a rocking lever with pivotal connections to said presser foot and feeding foot bars, and with an arm extending downward from one of its said connections, and eccentric crank means on one of said shafts operatively connected to said downward-extending lever arm, to rock said lever.

5. In a needle-feed sewing machine, the combination with a frame carrying a work support and including an arm overhanging said work support, a presser-foot bar mounted on said arm, a reciprocating needle bar, and an upper feeding foot bar, and a guide for the movement of said needle and feeding foot bars rockably fulcrumed

on said arm, of upper and lower shafts above the guide fulcrum mounted in bearings on said arm, with actuating connections from the lower shaft to said needle bar for reciprocating it, and from the upper shaft to said guide, above the actuating connection to the needle bar, for rocking the guide, a rocking lever fulcrumed on said arm with

pivotal connections above said drive shaft to said presser foot and feeding foot bars, and means for actuating said lever from said lower shaft connected to the lever below its said pivotal connections.

GEORGE SAUER.
